United States Patent Office

Des. 195,925
Patented Aug. 6, 1963

195,925

DISPLAY STAND

William E. Stumpf, Ross Township, Allegheny County, Pa., assignor to The Alan I W Frank Corporation, Pittsburgh, Pa., a corporation of Pennsylvania

Filed Sept. 14, 1962, Ser. No. 71,700

Term of patent 14 years

(Cl. D80—11)

Fig. 1.

Fig. 2.

Fig. 3.

I claim:

The ornamental design for a display stand, as shown and described.
